OFF-PEAK WATER HEATING SYSTEM

Herman M. Biebel, Elgin, Ill., assignor to McGraw
Electric Company, Elgin, Ill., a corporation of
Delaware

Application March 31, 1941, Serial No. 385,978

6 Claims. (Cl. 219—39)

My invention relates to control systems and particularly to water heating control systems.

The main object of my invention is to provide a relatively simple off-peak water heating system including a minimum number of elements co-operative to obtain the desired result.

Another object of my invention is to provide an off-peak water heating system effective to either start heating of the water at the beginning of an off-peak period or after a delay after the start of an off-peak period, depending upon the amount of hot water in the tank at the start of an off-peak period.

Other objects of my invention will either be apparent from a description of several modifications embodying my invention or will be pointed out hereinatfer in the course of such description and set forth in the appended claims.

In the drawing:

Figure 1 is a view of a domestic hot water tank with a diagrammatical layout of a control system embodying my invention, the parts being shown in positions they will occupy just before the start of an off-peak period and with the tank containing cold water.

Fig. 2 is a fragmentary view similar to Fig. 1 but showing parts of the control means in the positions they will occupy at the start of an off-peak period and with the tank partly full of hot water, and,

Fig. 3 shows a modification of my improved water heating system, the parts being shown in the positions they will occupy when the tank is substantially filled with cold water.

I have elected to show my improved hot water heating system as applied to a domestic tank 11, shown as being of cylindrical shape and relatively tall, although my invention is not limited thereto. I provide a cold water inlet pipe 13 and a hot water outlet pipe 15 suitably connected to the tank 11 which may be surrounded by heat insulating material 17 which may be protected by an outer casing 19, all in a manner well known in the art.

I provide an electric heater 21 which, for convenience, may be clamped around the outside of the tank 11 near the lower end thereof and be located in a tunnel 23. Here again, however, I have shown the heater generally only and may use any other heater now well known in the art for the desired purpose.

I provide a continuously operative timing means which is shown as including an electric motor 25 having a worm gear 27 mounted on its shaft which is adapted to mesh with a worm

wheel 29. While I have shown a worm gear and a worm wheel for illustrative purposes, I desire it to be understood that the object is to provide a clock or continuously operative timer effective to cause one revolution of a certain part of the system once in twenty-four hours and any mechanical means for obtaining this purpose may be employed by me in place of the worm gear and worm wheel shown in the drawing.

10 The worm wheel 29 is fixedly mounted on a rotatable shaft 31 and while I have not shown any bearing for this shaft, it is, of course, understood that such means are provided to permit of rotating the shaft 31 by the motor 25.

15 I provide a stationary cam disk 33 loosely mounted on the shaft 31, which cam disk has a larger part of its outer periphery of a uniform radius, which radius is less than the outer radius of a portion 35 which portion 35 constitutes, in effect, a part of the off-peak period desired by the utility providing the electric current to operate the system and energize the heater 21. The cam disk 33 is held stationary by any suitable means, not shown.

20 25 I have shown a supporting bearing bracket 37 which may be suitably supported from or by the tank 11 at its lower end and I further show a tubular bushing 39 movably mounted on the shaft 31 at that end thereof near the tank 11. The bushing 39 is provided with a radially extending arm 41 having insulatedly mounted thereon a member 43 of electric conducting material which member has a peripheral extent of such dimension that when added to the peripheral extent of portion 35 of disk 33, the time covered by the leading portion 43 and the trailing portion 35 will equal the desired off-peak period. Member 43 is insulated from arm 41, for a purpose which will hereinafter appear.

30 40 I provide an annular ring 45 mounted on and insulated from the shaft 31 which contact ring is adapted to be engaged by a brush 47. I further provide a supporting arm 49 fixedly mounted on shaft 31 which arm is adapted to support a brush or contact arm 51 shown as being supported by arm 49 by means of a block 53 of electric insulating material. Contact ring 45 is connected to brush 51 by a conductor 55. It is understood that cam disk 33 is either of electric 45 50 conducting material or that the portion 35 thereof, of larger outer radius, is of electric conducting material since it is desired to have the brush 51 engage the portion 43 as well as the portion 35 to close an electrical circuit, as will be hereinafter described.

I desire to adjust the peripheral position of member 43 in accordance with the average or integrated temperature of the water in the tank 11 or, as may be stated in other words, in accordance with the heat condition or the heat content of the tank. For this purpose I provide a rod 57 which is shown as being of non-expansive material, now well known in the art, which has its upper end supported by a bracket 59 which may be secured in any suitable or desired manner to the upper end of the tank. The lower end of rod or bar 57 may have a plurality of teeth cut there-in which will enable it to mesh with an end portion of the bushing 39 whereby longitudinal movement of the lower end of the rod 57 will cause turning movement of bushing 39 and therefore an angular or peripheral movement of portion 43 of the contact comprising two relatively adjustable members 43 and 35 adapted to be engaged by brush 51.

A pair of supply circuit conductors 61 and 63 are shown to which the terminals of the motor 25 are permanently connected. Supply circuit conductor 61 is connected by a conductor 65 with brush 47. Supply circuit conductor 63 is connected by a conductor 67 with one terminal of the heater 21, the other terminal of which is connected to one terminal of a thermal heater control switch 69 which is shown as including a bimetal bar 71 having one end secured to a block 73 or other suitable support which is understood to be in heat-receiving relation with the tank 11 or with the water in the tank. Thermal switch 69 includes further a fixed contact member 75 adapted to engage with and be disengaged from the free end of bimetal bar 71. Contact 75 is connected through a conductor 77 with the electric conducting member 43.

Let it be assumed that the tank 11 has just been filled with cold water and that the parts are in the position shown in Fig. 1 of the drawing, that is, just before the start of an off-peak period. Since the tank is full of cold water and the design, construction and adjustment of the heater, the thermal heater control switch and the continuously operative timing means hereinbefore described are such that substantially all of the off-peak period is required to heat all of the water in the tank during an off-peak period, the member 43 is shown in the position which it will occupy relatively to the portion 35 of the contact surface. As soon as brush 51 engages member 43, which may be called the auxiliary leading portion, a circuit through the heater 21 will be established substantially as follows: From supply circuit conductor 61 through conductor 65 and brush 47 to the contact ring 45, through conductor 55 and brush 51 to the leading portion 43 and from there through a suitable conductor 79 through conductor 77 to contact member 75, through bimetal bar 71 which will be in engagement with contact member 75 under the assumed conditions and from there through heater 21 and conductor 67 to the other supply circuit conductor 63. This will therefore energize the heater 21 at substantially the beginning of an off-peak period. I have shown the peripheral extent of the main trailing portion 35 and of the movable auxiliary leading portion 43 as extending over substantially one-third of the entire periphery, that is, the time extent will be substantially eight hours. For illustrative purposes it may be assumed that such maximum off-peak period or energization of the heater will start at 10 p. m. and extend to substantially 6 a. m.

While I have hereinbefore stated that the position of the leading portion 43 of the contact surface adapted to be engaged by brush 51 is that corresponding to the condition when the tank is entirely full of cold water, I do not desire to be limited thereto since it is possible to so construct and adjust the operative parts of my system, particularly that of the auxiliary leading portion 43 of the contact surface, so that the position shown in Fig. 1 of the drawing will correspond to that condition of the tank when a predetermined fractional part of the water content is hot.

Fig. 2 of the drawing shows the condition when the tank is not entirely filled with cold water but when it contains a predetermined fractional part of hot water with the result that the leading portion 43 overlaps the trailing portion 35 and the brush 51, which is moved continuously in a clockwise direction, will not engage portion 43 at as early a time as it would have engaged member 43 under the conditions shown in Fig. 1 of the drawing. The adjustment of the system is, of course, such that the entire content of the tank will be heated shortly before the end of an off-peak period, that is, the energization of the heater 21 will be effected to occupy the "valley" of the load curve on the central station.

It is further obvious that should all of the water in the tank be heated to the desired high temperature before the end of the off-peak period, the bimetal bar 71 would flex and disengage from the contact member 75. It is further evident that should a withdrawal of hot water from the tank occur during the rest of the off-peak period, the bimetal bar 71 would again engage contact member 75 and reenergization of the heater 21 would occur and might continue until deenergization of the heating system occurs at the end of an off-peak period when contact brush 51 would move out of engagement with the trailing portion 35.

Referring now to Fig. 3 of the drawing, I have there illustrated a modified form of system in which certain parts of the system hereinbefore described are used in combination with others whereby I am enabled to obtain other results than are obtained by the use of the system shown in Figs. 1 and 2.

I provide an electric motor 25 having a worm gear 27 on its shaft meshing with and driving a worm wheel 29 which worm wheel 29 is fixedly mounted on a shaft 81. It is to be understood that while no particular supporting means have been shown for shaft 81, these are to be provided in a manner well known in the art.

I provide a fixed arcuate contact surface 83 which may be fixedly mounted on a suitable supporting means 84 of electric-insulating material. I provide further an adjustable leading contact surface 85 which is supported by a bushing 87 movably mounted on shaft 81 to which the portion 85 is connected as by an arm 89. The bushing portion 87 is provided with teeth to permit of meshing with the toothed lower end of a non-expansion rod 57 of the same general kind as hereinbefore described in connection with Fig. 1 of the drawing. I provide further a second bushing 91 fixedly mounted on shaft 81 and having either secured thereto or integral therewith a brush or contact arm 93 which is adapted to engage the movable auxiliary leading portion 85 and the fixed main trailing portion 83 of the contact surface which has substantially the same operation as the members 43 and 35 hereinbe-

fore described in connection with Figs. 1 and 2 of the drawing.

I provide in addition to the thermal heater control switch 69 subject to the temperature of the water in the lower portion of the tank, a second heater control switch comprising an electromagnetic coil 95 adapted to energize a movable core member 97. A main contact bridging member 99 and an auxiliary holding circuit contact bridging member 101 are mechanically connected with the movable core 97 to be moved into engagement with, respectively, fixed main heater circuit contact members 103 and auxiliary fixed holding circuit contact members 105. Supply circuit conductor 61 is connected by a conductor 107 with one of the fixed contact members 103 and 105, while the other fixed contact member 103 is connected by a conductor 109 with one terminal of the heater 21. The other terminal of heater 21 is connected to contact member 73 and contact member 75 is connected by a conductor 111 with the other supply circuit conductor 63. Supply circuit conductor 61 is connected by a conductor 113 with brush 51 and the two electrically connected contact surfaces 85 and 83 are connected by a conductor 115 with one terminal of coil 95. The other terminal of coil 95 is connected by a conductor 117 with contact member 73 of the thermal switch 69.

When brush 93 is engaged with the leading contact surface 85 moved peripherally relatively to the trailing portion 83 in accordance with the average water temperature of the heat content of the tank, an energizing circuit through coil 95 will be established as follows: From supply circuit conductor 61, through conductor 113, brush 51 to bushing 91, through arm 93 and through the contact surfaces 85 and 83 and the mechanical support 84 supporting the latter, through conductor 115, coil 95, through conductor 117, through the thermal switch 69 and from there through conductor 111 to the other supply circuit conductor 63. This energization of coil 95 will cause upward movement of core 97 and of the contact bridging members 99 and 101 into engagement with the respective fixed contact members 103 and 105 whereby an energizing circuit through the heater 21 is established, as well as a holding circuit for the coil 95. The energizing circuit through heater 21 is substantially as follows: From supply circuit conductor 61 through conductor 107, through engaged contact members 103 and 99, through conductor 109, through heater 21 and then thermal heater control switch 69 and from there through conductor 111 to the other supply circuit conductor 63. The holding circuit established is as follows: From supply circuit conductor 61 through conductor 107 to one of the fixed contact members 105, from there through the engaged contact member 101 and 105 and a conductor 119 to and through coil 95 and from there through conductor 117 and the closed thermal switch 69 through conductor 111 to the other supply circuit conductor 63.

The position of the thermally movable auxiliary leading contact surface 85 is the same as was hereinbefore described in connection with the system shown in Fig. 1 of the drawing. That is, if the tank contains either a large amount of cold water or is entirely full of cold water at the start of an off-peak period, the relative positions of the leading and the trailing portions of the contact surface is substantially that

shown in Fig. 3 of the drawing but the leading portion 85 may occupy the position shown in the broken lines in Fig. 3 of the drawing if the tank contains an appreciable amount of hot water which can be heated in less than an entire off-peak period.

It is further evident that the holding circuit described above is entirely independent of the engagement of brush 93 with the contact surface 85 and 83 so that should it happen that all of the water in the tank is not hot at the end of an off-peak period because of the fact that appreciable amounts of hot water were withdrawn from the tank during the later part of an off-peak period, energization of the heater 21 will continue beyond the end of an off-peak period and in fact will continue until substantially all of the water in the tank is hot, at which time bimetal bar 71 will flex to be disengaged from the fixed contact 75 whereby the holding circuit of the electromagnetic switch and particularly of the coil 95 is interrupted with attendant deenergization of the coil 95, opening of the electromagnetic switch contacts and therefore deenergization of the heater 21.

A normally open push button switch 121 may be provided, one fixed contact 123 thereof being connected to supply circuit conductor 61 while the other fixed contact member 123 is connected by a conductor 125 to conductor 115. When the switch 121 is closed manually and momentarily by an operator, an energizing circuit through the coil 95 will be established as can easily be traced from Fig. 3 of the drawing with the result that contact bridging member 99 is moved into engagement with contact members 103 whereby the heater 21 is energized while at the same time the hereinbefore described holding circuit is established by engagement of contact bridging member 101 with the fixed contacts 105. Should it happen accidentally or because of unusual demands for hot water during the day, that is, during the on-peak period of a day, that the user of such a system would desire or require hot water, all that it would be necessary to do would be to close switch 121 momentarily when the heater would be energized, such energization continuing until all of the water in the tank is hot when deenergization of the heater 21 would occur, all as described above.

The water heating systems embodying my invention and disclosed in the present application therefore are effective to cause energization of the heater of a hot water tank at a time varying in accordance with the amount of hot water in the tank at the start of an off-peak period, energization being delayed if the tank contains more than a predetermined amount of hot water. The systems will either cause deenergization of the heater at the end of an off-peak period when the modification shown in Fig. 1 of the drawing is used or energization may continue beyond the end of an off-peak period when a second heater control switch of the electromagnetic type is used as shown in Fig. 3 of the drawing.

Various modifications may be made without departing from the spirit and scope of the invention and I desire that all such modifications clearly coming within the scope of the appended claims shall be considered to be covered thereby.

I claim as my invention:

1. In an off-peak water heating system for a tank having an electric heater, a switching means for controlling said heater including a movable contact member, a constantly operative timer

adapted to move said contact member in a given path, a contact surface extending over an off-peak portion of said given path and comprising a fixed main trailing portion and a movable auxiliary leading portion and means responsive to the average tank water temperature for fixing the position of said auxiliary leading portion of said cam surface to cause engagement of said cam surface by said movable contact member at a time during an off-peak period which is later when the average tank water temperature is high than when it is low.

2. In an off-peak water heating system for a tank having an electric heater, a switching means for controlling said heater including a movable contact member, a constantly operative timer adapted to move said contact member in a given path, a contact surface extending over an off-peak portion of said given path and comprising a fixed main trailing portion and a movable auxiliary leading portion and means responsive to the average tank water temperature for fixing the position of said auxiliary leading portion of said cam surface to cause engagement of said cam surface by said movable contact member at a time after the start of an off-peak period which time increases in accordance with the excess of the average tank water temperature above a predetermined value.

3. In an off-peak water heating system for a tank having an electric heater, an electromagnetic heater control switch and a thermally-actuable heater control switch electrically connected in series circuit with each other, a continuously operative timer, a movable contact member adapted to be moved in a given path by said timer, a contact means having a surface engageable by said movable contact member and extending over an off-peak portion of said given path and comprising a fixed trailing main portion and a movable leading auxiliary portion and means responsive to the average tank water temperature for moving said leading auxiliary portion of said contact means relatively to said main portion to cause engagement of said movable contact member with said leading auxiliary portion and energization of the electromagnetic switch and of the electric heater after a length of time after the start of an off-peak period which length of time increases in proportion to the excess of hot water in the tank over a predetermined amount.

4. In an off-peak water heating system for a tank having an electric heater, an electromagnetic heater control switch and a thermally-actuable heater control switch electrically connected in series circuit with each other, a con-

tinuously operative timer, a movable contact member adapted to be moved in a given path by said timer, a contact means having a surface engageable by said movable contact member and extending over an off-peak portion of said given path and comprising a fixed trailing main portion and a movable leading auxiliary portion and means responsive to the average tank water temperature for moving said leading auxiliary portion of said contact means relatively to said main portion to cause engagement of said movable contact member with said leading auxiliary portion and energization of the electromagnetic switch and of the electric heater after a length of time after the start of an off-peak period which length of time increases in proportion to the excess of hot water in the tank over a predetermined amount and for causing deenergization of said heater when substantially all of the water in the tank is hot.

5. In an off-peak water heating system for a tank having an electric heater, an electromagnetic heater control switch and a thermally-actuable heater control switch electrically connected in series circuit with each other, a continuously operative timer, a movable contact member adapted to be moved in a given path by said timer, a contact means having a surface engageable by said movable contact member and extending over an off-peak portion of said given path and comprising a fixed trailing main portion and a movable leading auxiliary portion and means responsive to the average tank water temperature for moving said leading auxiliary portion of said contact means relatively to said main portion to cause engagement of said movable contact member with said leading auxiliary portion and energization of the electromagnetic switch and of the electric heater after a length of time after the start of an off-peak period which length of time increases in proportion to the excess of hot water in the tank over a predetermined amount for causing deenergization of said heater when substantially all of the water in the tank is hot and for causing reenergization of said heater in case withdrawal of hot water from the tank during the rest of an off-peak period substantially reduces the amount of hot water in the tank.

6. A system as set forth in claim 3 and including a normally open switch movable into momentarily closed position to cause energization of said electromagnetic switch and of said heater at any desired time during an on-peak period in case less than all of the water in the tank is hot, said energization of the heater continuing until substantially all of the water in the tank is hot.

HERMAN M. BIEBEL.
